UNITED STATES PATENT OFFICE.

OTTO SPANNAUS, OF COLOGNE-MULHEIM, GERMANY, ASSIGNOR TO FELTEN AND
GUILLEAUME CARLSWERK ACTIENGESSELLSCHAFT, OF COLOGNE-MULHEIM, GERMANY.

COUPLING FOR STEEL-ALUMINUM ROPES.

Application filed August 8, 1922. Serial No. 580,506.

To all whom it may concern:

Be it known that I, OTTO SPANNAUS, a citizen of Germany, and resident of Cologne-Mulheim, Germany, have invented a new and useful Improvement in a Coupling for Steel-Aluminum Ropes, of which the following is a full, clear, and exact specification, reference being had therein to the accompanying drawing.

10 This invention relates to a coupling for steel aluminum cables that is, for cables of two concentric layers of different metals, the outer layer consisting of aluminum. The coupling must be kept as short as possible 15 so as to offer only a small surface to the wind pressure and in order to save costs and weight.

Conical couplings are known in connection with ordinary stranded wire ropes, but 20 it never has been proposed to employ couplings for cables of two concentric layers of different metals, consisting of hollow concentric cones within a conical sleeve, all adapted to grip separate layers of wire of 25 different metals between the contiguous surface and arranged concentrically one within the other, so as to be drawn into one another by the tension exerted upon the cable.

The present invention consists in this that 30 in cables of the kind first referred to the ends of the core of steel wires and of the surrounding wires of aluminum are firmly pressed by special hollow cones which lie concentrically one within the other. In the 35 event of the aluminum wires giving, the cones are always automatically drawn into one another by the tension exerted on the cable and thereby always press the wires again firmly against the walls of the cones 40 so that good electric contact is always maintained.

Reference is now made to the accompanying drawings in which Figure 1 is a longitudinal sectional view of a coupling according 45 to the invention, and Figure 2 is a sectional view of a terminal or detachable connector.

Referring to Figure 1, the wires *f* of the steel core are clamped by a hollow cone *e*, 50 against the inner surface of the concentrically arranged intermediate hollow cone *a*.

The aluminum wires *d* are pressed by the hollow cone *a* against the inner surface of the conically bored sleeve *b*. Two conical sleeves *b* are connected together by means of 55

a sleeve *c* preferably threaded. *g* is an intermediate piece, which has the purpose of providing an abutment and of avoiding the wires projecting too far and becoming entangled with the wires on the other side. 60 The piece *g* is made of any suitable metal and not being essential may be omitted.

According to experience, aluminum wires held in cones easily give and are then liable to become fused. Should this occur in the 65 coupling according to the invention, that is, should the outer aluminum wires *d* give, the tension exerted on the steel wires *f* causes the wires *f*, together with the cone *e* to be drawn further into the cone *a*. This causes 70 the cone *a* to be drawn further into the cone *b*, so that, by the tension exerted in the cable, in the event of the wires giving, the entire arrangement is automatically tightened again and the wires always remain 75 pressed firmly against the walls of the cone and of the conical sleeve *b*. This always ensures a good electrical contact, even in case the steel wires should have to take over the conduction of the current through any 80 cause, as the current will then pass to the other side by way of *a*, *b*, *c*. This coupling can also be used for detachably connecting the end of the cable to an insulator, see Figure 2 for instance by screwing to the threaded sleeve *c* a threaded bolt *h* having a shank and an eye. 85

Having now fully described and ascertained the nature of my invention and in what manner the same is to be performed I 90 declare that what I claim is,

1. A cable coupling for steel-aluminum cables comprising in combination inner and intermediate cone members arranged concentrically and between which the steel wires are held, an outer conical sleeve arranged concentrically over said intermediate cone member and between which the aluminum wires are held, so that the tension exerted upon the cable automatically pulls the inner and intermediate conical members into the conical sleeve thereby firmly gripping the wires against the conical walls. 95

2. A cable coupling for steel-aluminum cables comprising in combination two sets 100 of inner and intermediate cone members each set arranged concentrically and between which the steel wires of the cable are held, two screw threaded outer conical sleeves arranged concentrically one each over said in- 110

termediate cone members and between which the aluminum wires are held and means for connecting together the two conical sleeves.

3. A cable coupling for steel-aluminum cables comprising in combination two sets of inner and intermediate cone members each set arranged concentrically and between which the steel wires of the cable are held, two screw threaded outer conical sleeves arranged concentrically one each over said in-

termediate cone members and between which the aluminum wires are held and a screw threaded sleeve for connecting together the two conical sleeves.

In testimony whereof I have signed my name in the presence of two witnesses.

OTTO SPANNAUS.
